HERBERT J. PERCY, OF LYNN, MASSACHUSETTS, ASSIGNOR TO UNITED SHOE MACHINERY COMPANY, OF PATERSON, NEW JERSEY, A CORPORATION OF NEW JERSEY.

MANUFACTURE OF WELT-SHOES.

1,141,912.

Specification of Letters Patent. Patented June 1, 1915.

Original application filed September 9, 1910, Serial No. 581,179. Divided and this application filed August 17, 1911. Serial No. 644,498.

To all whom it may concern:

Be it known that I, HERBERT J. PERCY, a subject of the King of England, residing at Lynn, in the county of Essex and State of Massachusetts, have invented certain Improvements in the Manufacture of Welt-Shoes, of which the following description, in connection with the accompanying drawings, is a specification, like reference characters on the drawings indicating like parts in the several figures.

This invention relates to the manufacture of shoes and particularly welt shoes and this application is a division of application Serial No. 581,179, filed September 9, 1910. In making shoes of this type an innersole is used upon the bottom face of which from the heel seat around the forepart, is raised by channeling or otherwise, a lip or shoulder and to the outer face of this lip the stretched or lasted upper is sewed; together with the welt by which the outersole is later to be connected to the shoe. The process of lasting or stretching the upper over the last and working it into position to be secured is usually accompanied or followed by the application of temporary fastening means such as tacks which hold the upper while it awaits presentation to the sewing machine. With the upper materials of the rear portion of the shoe is included a heel stiffener the body portion of which stands up between the upper and lining around the heel of the wearer's foot and the flange of which is turned inwardly under the foot. This stiffener is made of some slightly flexible material such as stiff sole leather or leather-board which is commonly prepared by compression and molding to reduce flexibility and increase shape retaining qualities. These processes and the nature of the material are such that the stiffener is usually found to be hard and not readily penetrable and to have a smooth surface.

The attaching flange of the heel stiffener is molded, or is bent in the lasting operation, to lie flat down upon the heel seat end of the innersole to which it is attached, together with the lasted-over upper, by lasting tacks. These tacks of the heel seat are permanent fastenings, fully driven and clenched on the sole plate of the last, as contrasted with the lasting tacks of the shank and forepart which are only partially driven.

in anticipation of their withdrawal when their temporary use has been fulfilled. The wings or sides of the stiffener extend forwardly beyond the heel seat and into the shank and the flange is included in the rear portion of the "inseam," as the stitching is called, which connects the upper and the welt to the innersole lip. In practice difficulty has been encountered in sewing the end portions of the inseam and in obtaining a snug fitting of the upper of the finished shoe at these portions of each side of the shoe. The flange of the stiffener overlies the lip of the innersole and it bridges from the edge of the innersole up over the lip at a small angle to the path of the sewing machine needle and its hard smooth surface causes the needle to tend to slide along it without penetrating it. To lessen this tendency the operator changes the inclination at which he holds the shoe in order to present the hard material more nearly perpendicular to the path of the needle. In thus changing the inclination of the work the shoe is fulcrumed on the lower end of the channel guide, which is located at the inner side of the lip, and thereby the needle is also caused to enter the stock higher up on the lip whereas it should sew the stitch close down at the foot of the lip in order to make a firm connection with the innersole. The result is that the pressure applied to the shoe in the heel attaching operation spreads this loosely attached portion causing a mis-shaping of the shoe at this point. Special machines have been devised to tighten this stock over the last bottom, crush it down while held tightened and tack it in place. Another difficulty is that in stitching the first end of the inseam it is impracticable to get the sewing instrumentalities into position to begin the inseam close up to the adjacent fully driven heel seat tack and again in stitching the last end of the inseam the channel guide encounters the portion of the heel stiffener flange that is held down by the adjacent heel seat tack. This leaves a gap between the last stitch and the first tack and the channel guide also frequently pries up and loosens the tack. This adds to the need for re-tightening and further tacking which has come to be a general practice. By the present invention these manufacturing difficulties are obvi-

ated or very substantially reduced and the shoe is materially improved in appearance and strength and in accordance with a preferred practice of the invention, certain additional manufacturing advantages are secured which will be later explained.

In accordance with this invention the heel stiffener is shaped to present at the front portion of each wing an inturned flange and an upturned lip of substantially permanent form which lip and flange fit respectively upon the feather and against the outer face of the lip of the innersole at the time when the inseam stitching operation is performed. In order thus to shape the stiffener wings effectively, it appears to be necessary, because of the resistant character of the material of which the stiffeners are usually formed, to subject the wings to molding pressure in a well known manner between members sufficiently rigid to bend and compress the material to the required shape. In lasting the shoe the flange of the stiffener is positioned upon the feather of the innersole with the lip of the stiffener as close as practicable to the lip of the innersole. After the lasting operation the lip of the innersole and lip of the stiffener, together with the upper and the welt, are sewed together, the needle of the sewing machine passing through the stiffener lip in substantially perpendicular relation to the plane of the lip, and the flange and the lip of the stiffener are thereby drawn and held firmly in place so that there is no looseness in the lasted shoe at and near the ends of the stiffener.

In accordance with this invention, in a further novel aspect, the heel stiffener is formed at each side of the heel with a normally upturned portion, such as the lip above referred to, arranged to indicate the point at which to begin or to end the inseam. The rear end of the stiffener lip may conveniently serve as such an indication, and preferably at the rear of each lip, at the point where the lip meets the rear flange of the stiffener, I form a slit extending from the edge inwardly the width of the lip whereby the lip is separated from the flange in the rear of it and allowed to stand upright while the flange lies down flat upon the heel seat. I preferably form these slits in the two ends of the stiffener at points which will come under the heel of the shoe and they may conveniently be made before the stiffener is molded or before the molding operation is completed in which case the stiffener will be formed between the slits with a flange adapted to lie throughout its width upon the heel seat face of the inner sole and will be formed in front of said slits with a flange of a width corresponding with the width of the feather of the inner-sole and with a lip shaped to project at sub-

stantially right angles to said flange. The use of the slits prevents obstruction of the channel guide of the sewing machine in the inseam sewing operation and permits the inseam stitches to extend to the rear ends 70 of the lips. In a lasted shoe made in accordance with this invention the slits or the rear ends of the upright lips of the stiffener are, moreover, visible or otherwise discernible and I preferably make use of 75 these slits or lip ends as the indication points to guide the inseam sewing machine operator in beginning and terminating the inseam. Thus, if these slits are made at a correct distance from the rear end of the 80 stiffener, the operator is enabled to sew the shoe uniformly with respect to the ends of the inseam.

The accompanying drawings illustrate 85 how this invention may be practised.

Figure 1 is a plan view of a shoe having the upper materials, including the novel heel stiffener, assembled on a last, parts being broken away to show the new features more clearly; Fig. 2 shows the shoe after 90 one side has been lasted and the other side lasted and the weltting operation commenced, the needle and the channel guide of the sewing apparatus being shown in operative relation to one another and to the 95 work; Fig. 3 illustrates a portion of the last, heel stiffener, upper and welt showing the close fitting of the parts held by the inseam; Fig. 4 shows the old conditions by 100 way of contrast.

The last is indicated at 2, the innersole at 4, the lip thereof at 5, and the feather at 6. The body portion of the heel stiffener may be of usual form as may also be the rear portion of the flange 8. It should be here 105 stated that it is immaterial to the broad aspect of this invention whether the flange of the stiffener is turned inwardly in the molding operation, as in the stiffener herein illustrated, or is straight like that of many 110 heel stiffeners now used. In the latter case the flange is bent over the edge of the shoe bottom in the lasting operation. In either case the front portions or the wings of the stiffener are provided with upturned lips 115 10 located inwardly from the fold over the edge of the shoe bottom a distance equal to the width of the feather of the innersole. These lips 10 extend backwardly from the front ends of the wings as far as the lips 5 120 of the innersole go and are formed to fit smoothly against the outer face of said lips 5. The lip 10 may merge into the margin of the rear portion of the flange by a bend in the material but preferably it is separated 125 therefrom by a cut or incision at 15.

The shoe is assembled upon the last as usual and the upper materials may be secured in assembled relation for the pulling over and lasting operation by tacks located 130

as shown in Fig. 1 or in any other suitable location. In the lasting operation the flange of the heel stiffener is fastened down upon the heel seat end of the innersole and tacked, 5 Fig. 2, as usual and also is fastened down upon the feather of the innersole while the lips 10 are fastened firmly up against the outer face of the innersole lips 5. The lipped formation of the flange enables it to 10 conform closely to the angular faces of the feather and lip of the innersole instead of bridging from the innersole edge to the top of the lip as heretofore. When the shoe is presented to the weltor for sewing the inseam 15 the needle 16 approaches the hard material of the heel stiffener lip 10 in a direction substantially perpendicular to the plane of said lip and readily penetrates it. The lasting of the upper and the stiffener flange 20 down into the angle between the feather and lip of the innersole permits the stitches to be sewed down in said angle so that a connection of the parts of the shoe by these stitches is made which is as firm as or firmer 25 than that at any other portion of the inseam. The upstanding lips 10, particularly when bound into place by the stitches, form an effectual stiffener for the shank of the 30 shoe because of the well known resistance offered by stiff sheet material to bending edgewise. The incisions facilitate the commencement of the inseam with a stitch located at the very end of the lips 5 and 10 and close to the heel seat tack. The incision 35 on the second side of the shoe where the inseam is ended enables the channel guide 18 to pass without obstruction out of the inner channel of the innersole and over the portion of the stiffener flange which has been 40 tacked down. This prevents the channel guide from prying up the heel seat tack as heretofore and also it enables the inseam to be continued to the end of the lips 5 and 10 thus attaching the upper completely without 45 the interval which has been necessary between the tack and the last stitch and which required the insertion of an upper fastening tack after the inseam sewing operation. Inasmuch as the operator has not 50 been obliged to tip the shoe down over the channel guide as a fulcrum in order to present the work so that the needle would penetrate the stock instead of sliding along the hard stiffener the stitches have been located 55 close down at the base of the innersole lip and there is no looseness of the upper that requires to be tightened after the inseamming operation, nor is there any chance for the upper to bulge or spread outwardly under the heel attaching pressure because it is 60 firmly attached to the base of the innersole lip and cannot move outwardly as it could if attached to the upper edge of the lip which can tip sidewise.

65 Another advantage is found in the com-

pactness of the stock at the shank and heel breast which is obtained by fitting the stiffener flange firmly down upon the innersole feather. This brings the upper and the welt nearer to the plane of the innersole, giving a 70 "closer" rand crease and allowing the inseam to be trimmed more closely and also avoiding danger heretofore existing of cutting the inseam stitches while trimming the inseam at the ends. 75

Obviously a further advantage is in the use of the incisions 15 as guides for the operator in starting and finishing the inseam at predetermined points on each side of the shoe and at the same distance from the heel end of all shoes of the same size. The incisions 15 like the lips 10 may be made during the manufacture of the heel stiffeners and as a part of the molding or some other making operation. To mold a heel stiffener 80 to present at its ends an upstanding lip extending backwardly as far as the lip of the innersole and adapted to stand against the outer face of the innersole whereby the stiffener flange conforms to the shape of the 85 feather and lip when the stiffener is assembled in a shoe is a new step in the manufacture of shoes. 90

Having explained the nature of this invention and described how it may be practised, I claim as new and desire to secure by Letters Patent of the United States:— 95

1. That improvement in methods of making welt shoes which consists in molding a heel stiffener to present at the front portion 100 of each wing an inturned flange and an upturned lip, assembling said stiffener and a lipped innersole in co-operative relation, with said stiffener lips contiguous to the innersole lips, and sewing the lips of the 105 stiffener and innersole together.

2. That improvement in methods of making welt shoes which consists in molding a heel stiffener to present at the front portion of each wing a lip shaped to stand upwardly 110 from the face of the innersole at the same distance inwardly from the edge of the assembled shoe as the outer face of the innersole lip, assembling parts of the shoe including said stiffener, an innersole and an upper, 115 and lasting the shoe with said lips of the stiffener and innersole in contact with each other.

3. That improvement in methods of making welt shoes which consists in molding a heel 120 stiffener prior to the lasting operation to present at the front portion of each wing an upturned lip, assembling the stiffener and an innersole with said lip standing up edgewise relatively to the face of the inner sole from 125 the heel seat forwardly along the shank and securing the stiffener to the innersole.

4. That improvement in methods of making welt shoes which consists in slitting a heel 130 stiffener from its inner edge outwardly at

points which will come under the heel of the shoe, molding the stiffener to form at the rear thereof between the slits a flange to lie throughout its width upon the heel seat face 5 of the inner sole, and to form from said slits forwardly flanges of less width to lie on the feather of the innersole and lips projecting at substantially right angles to said flanges to stand against and parallel to the outer face 10 of the lip of the innersole, assembling the shoe, and sewing the lips of the innersole and stiffener together.

5. That improvement in methods of making shoes which consists in forming a heel stiffener at each side of the heel with a normally upturned portion arranged to indicate the points for the beginning and the ending of the inseam, assembling and lasting the shoe and inseaming the shoe from one indication 20 point around the forepart to the other indication point.

6. That improvement in methods of making shoes which consists in forming a heel stiffener at each side of the heel with a normally upturned portion adapted to stand exposed 25 to sight above the innersole lip in a lasted shoe and arranged to indicate to the inseamer the points at which to begin and to end the welt attaching seam, and inseaming the shoe 30 from the indicated point on one side around the toe to the other indicated point on the other side of the shoe.

7. That improvement in methods of making welt shoes which consists in forming a heel stiffener with an inturned flange at the front 35 portion of each wing and an upturned lip at the inner edge of the flange, assembling upon a last the stiffener so formed, together with an innersole and an upper, with said upturned lips adjacent to the lips of the innersole, lasting the upper over the inturned flange of the stiffener with the inner edge of 40 the upper extending upwardly against the stiffener lip, and securing said innersole lip, 45 stiffener lip and upper permanently together in said lasted position.

8. That improvement in methods of making welt shoes which consists in molding a heel stiffener to present at the front portion of 50 each wing an upturned lip located to stand at the same distance inwardly from the edge of the assembled shoe as the outer face of the innersole lip, assembling the stiffener and innersole with said lips adjacent to each other, lasting the shoe, and securing said parts 55 permanently in assembled relation.

9. That improvement in methods of making welt shoes which consists in shaping a heel

stiffener by molding pressure to form a normally upright lip positioned to stand against 60 the lip of the innersole in a plane substantially normal to the plane of the heel seat, and sewing the inseam with the needle passing through said stiffener lip in a direction substantially normal to the plane of said lip. 65

10. That improvement in methods of making welt shoes which consists in so shaping a wing portion of a heel stiffener as to conform it to the angle between the feather and the lip of the innersole and to form thereon a normally upright lip located to stand against the lip of the innersole in a plane substantially normal to the plane of the heel seat, and then sewing the inseam with the needle passing through said stiffener lip in a 70 direction substantially normal to the plane of said lip and close to the plane of the inner-sole. 75

11. That improvement in methods of making welt shoes which consists in shaping a 80 wing portion of a heel stiffener by molding pressure to conform it closely to the angle between the feather and the lip of the inner-sole and to form thereon a normally upright lip, and sewing the inseam with the needle 85 passing through said stiffener lip in a direction substantially normal to the plane of said lip and close to the plane of the inner-sole.

12. That improvement in methods of making welt shoes which consists in shaping a wing portion of a heel stiffener by molding pressure to conform it closely to the angle between the feather and the lip of the inner-sole and to form thereon a normally upright 95 lip, and terminating the rear end of said stiffener lip at the distance from the rear end of the stiffener at which the inseam stitching should terminate to indicate to a welt sewing machine operator the point at 100 which the inseam should begin, assembling said stiffener with upper materials closely about the heel end of a last to locate said indication point lengthwise of the shoe, and sewing the inseam from said indicated point 105 with the needle passing through said stiffener lip in a direction substantially normal to the plane of said lip and close to the plane of the innersole.

In testimony whereof I have signed my 110 name to this specification in the presence of two subscribing witnesses.
